UNITED STATES PATENT OFFICE

138,085

DESIGN FOR A TOY PISTOL

David Krechman, Chicago, Ill.

Application March 1, 1944, Serial No. 112,757

Term of patent 3½ years

(Cl. D34—15)

To all whom it may concern:

Be it known that I, David Krechman, a citizen of the United States, residing at Chicago, in the county of Cook and State of Illinois, have invented a new, original, and ornamental Design for Toy Pistols, of which the following is a specification, reference being had to the accompanying drawing, forming a part thereof.

Fig. 2 is an elevation showing one side of the toy pistol, the opposite side not shown in the drawing being similar;

Fig. 3 is an end view of the piston and,

Fig. 4 is an elevation of the opposite end thereof.

I claim:

The ornamental design for a toy pistol, substantially as shown and described.

DAVID KRECHMAN.
